The ornamental design for a cap, as shown and described.

DESCRIPTION

FIG. 1 is a top and front perspective view of a cap showing our new design;

FIG. 2 is a front elevational view of FIG. 1;

FIG. 3 is a back elevational view of FIG. 1;

FIG. 4 is a right side elevational view of FIG. 1;

FIG. 5 is a left side elevational view of FIG. 1;

FIG. 6 is a top plan view of FIG. 1;

FIG. 7 is a bottom plan view of FIG. 1; and,

FIG. 8 is an isometric view of the cap showing the cap in use on an unclaimed cup.

The broken lines in FIG. 7 depict portions of the cap that form no part of the claimed design. The broken lines in FIG. 8 represent environmental subject matter and form no part of the claimed design.

1 Claim, 5 Drawing Sheets(56)
